C. E. REDDIG

PRIME MOVER DYNAMO PLANT

Filed May 28, 1923

Inventor:
Charles E. Reddig.
by *Jed W. Palmer, Atty.*

UNITED STATES PATENT OFFICE.

CHARLES E. REDDIG, OF KEW GARDENS, RICHMOND HILL, NEW YORK, ASSIGNOR TO
WESTERN ELECTRIC COMPANY, INCORPORATED, OF NEW YORK, N. Y., A COR-
PORATION OF NEW YORK.

PRIME-MOVER DYNAMO PLANT.

Application filed May 28, 1923. Serial No. 641,802.

To all whom it may concern:

Be it known that I, CHARLES E. REDDIG, a citizen of the United States, residing at Kew Gardens, Richmond Hill, Long Island, 5 in the county of Queens, State of New York, have invented certain new and useful Improvements in Prime-Mover Dynamo Plants, of which the following is a full, clear, concise, and exact description.

10 This invention relates to prime mover dynamo plants, and particularly to such plants employing an internal combustion engine to drive a generator used to charge a storage battery. Its primary object is to 15 regulate automatically the output of the generator.

It is often desirable to secure a tapering charge for a storage battery, and many methods have been suggested to regulate a 20 prime mover and generator in order to accomplish this result. Among them is the method described and claimed in C. E. Reddig, Serial No. 602,026, filed November 20, 1922 which consists in regulating the speed 25 of an internal combustion engine through its timer mechanism in accordance with the height of the fuel in the fuel supply tank of the engine. In some cases, however, it is necessary to regulate the speed of the engine more accurately or to obtain a greater 30 reduction in the speed of the engine of the generator in response to a definite lowering of the height of the fuel; and this invention provides means whereby these aims may be 35 attained.

These means comprise a float in the fuel supply tank of the engine and connections between it and the throttle valve thereof, including, when a quicker reduction of the 40 engine speed is desired, means to also control the operation of the ignition timer.

The drawing shows one embodiment of the invention, Fig. 1 being an elevation of the entire plant, the vaporizer and tank being shown in section, and Fig. 2 being a sectional view of the vaporizer.

An internal combustion engine 5 operates a dynamo electric machine 7 having leads 8 and 9 connected to the terminals thereof. 50 A battery 10 is connected across these leads, and a load such as electric lamps 11 may also be inserted across them. A switch 12 may, if desired, be provided to connect the load into or out of the circuit. The crank

shaft 13 of the engine is geared to the cam 55 shaft 14 upon which is rotatably mounted a disc 15 bearing the ignition timer mechanism.

The engine is provided with a tank 16 to hold the fuel supply therefor. A pipe 17 60 conducts this fuel to the vaporizer 18 where the amount of the mixture supplied to the engine is controlled by a plunger throttle 20 set therein. A float 25 placed in the fuel tank is connected to a wing 26 on the disc 15 by means of a rod 27 so that the disc 65 may be rotated to retard the timing of the engine as the height of fuel in the tank decreases.

It is often desirable to limit the tapering 70 of the battery charge to a certain portion of the charging operation; and to this end the clockwise rotation of the disc 15 may be limited by a movable nut 28 fastened upon rod 27 a certain distance above a cap 29 set 75 on the top of the fuel tank, while its movement in a counter-clockwise direction may be limited by a vertically adjustable screw 30 set in a projection 31 above wing 26.

A rod 32 attached to plunger 20 is fastened to the side of disc 15 opposite the wing 26, and serves to move the plunger 20 upwardly to reduce the volume of the mixture supplied to the engine as the fuel in the tank is diminished. Thus the engine speed 85 may be reduced by two means during the battery charging or during any desired portion thereof so as to taper the battery charge with the desired celerity. If it is desired to control the engine speed through the 90 throttle alone, rods 27 and 32 may be connected by means other than the timer mechanism. Other changes may of course be made in the arrangement without departing from the spirit and scope of the invention. 95

The invention claimed is:

1. In combination, an internal combustion engine, a generator driven thereby, a storage battery to be charged by the generator, 100 a fuel supply tank, an ignition timer, and a throttle valve for the engine, and means including the throttle valve and the timer for controlling the speed of the engine in response to the height of the fuel in said tank.

2. In combination, an internal combustion engine, a generator driven thereby, a storage 105

2
battery charged by the generator, said engine comprising a fuel supply tank, an ignition timing mechanism, and a throttle valve, a float in the tank, and connections between the float, the timer, and the throttle valve so that the timing of the engine is retarded and the amount of the mixture supplied to it diminished as the fuel in the supply tank becomes exhausted.

19 3. In combination, an internal combustion engine, a generator driven thereby, a storage battery to be charged by the generator, a fuel tank and a throttle valve for the engine, a float in the tank, connecting means between the float and the throttle valve to control the amount of the mixture supplied to the engine, and adjustable means to limit the movement of said float.

4. In combination, an internal combustion engine, a dynamo electric machine driven

thereby, a storage battery to be charged by the dynamo electric machine, said engine comprising a fuel supply tank, ignition timing mechanism and a throttle valve, a float in the fuel supply tank, connecting means between the float and the timing mechanism whereby the latter is regulated in accordance with the height of the fuel in the tank, adjustable means for controlling the movement of said float, connecting means between said timing mechanism and said throttle valve whereby the throttle valve is also controlled in accordance with the height of the fuel in said tank so as to regulate the amount of the mixture supplied to the engine. 25 30 35

In witness whereof, I hereunto subscribe my name this 25th day of May A. D., 1923.

CHARLES E. REDDIG.
